SPINNING AND TWISTING MACHINE

Fred M. Roddy, Providence, R. I., assignor to
H & B American Machine Company, a corporation of Maine

Application August 17, 1942, Serial No. 455,060

15 Claims. (Cl. 57—97)

This invention relates generally to textile apparatus and particularly to improvements in the driving system for the yarn feeding and drafting mechanisms of spinning, twisting and like machines.

One object of the invention is to provide a self-contained compact unit assembly of gears forming a driving system by which power is transmitted for operating the feeding and drafting elements of machines of this class, and in which the arrangement of parts is such that the unit can be readily attached to one end of such machine.

Another object of the invention is the provision of a driving system incorporating the change gears controlling the twist on both sides of the machine in which the arrangement is such that it can be handled as a fully assembled unitary structure and at the same time will afford a wide degree of flexibility in that it is adaptable to produce a wide range of front roll speeds.

Another object of the invention is to provide low tooth speed and a uniform tooth speed regardless of the amount of twist that is being inserted in the yarn.

Another object of the invention is the provision of independent twist on both sides of the machine, and at the same time to permit reversibility of twist whereby either right or left hand twist can be readily and simply effected.

Another object of the invention is the provision of a gear drive unit of the above character wherein all gears are mounted on ball bearings and the number of said ball bearings and associated studs in the gearing system are reduced to a minimum.

With the above and other objects in view, the invention consists in the novel features of construction and operation of the several parts of the mechanism which is described in the following specification with reference to the accompanying drawings and defined in the appended claims.

The invention is illustrated by way of example in the drawings, in which

Fig. 1 is an end elevation of the head end of a twister embodying the present invention;

Fig. 2 is a front elevation of my improved unit mount having the swing arms mounted thereon but with all gears, ball bearings and studs omitted;

Fig. 3 is a transverse section taken on the line 3—3 of Fig. 1;

Fig. 4 is a vertical section taken on the line 4—4 of Fig. 2;

Fig. 5 is a perspective view showing the bottom

face of the swing arm which carries the two idler gears;

Fig. 6 is a perspective view of the bottom face of the other swing arm;

5 Fig. 7 is a fragmentary detail view of an upper corner portion of the unit mount showing the driving arrangement for one of the change gears; and

Fig. 8 is a vertical section taken on the line 10 8—8 of Fig. 7.

In conventional machines of this class the driving system for the front rolls of the yarn feeding and drafting mechanisms at both sides of the machine usually comprises a considerable 15 number of large diameter gears arranged in a train between a pinion gear on the main drive shaft and the front draft rolls. These large intermediate gears are made with plain shaft bearings and are rotatably mounted on plain studs. 20 The bearings are oiled from the outside of the frame through tubes conveniently located and fitted with exterior oil cups. The change gears, of which there are two when the arrangement provides for independent twist, are usually mounted 25 on swing arms and the change gears are keyed to the same stud shaft to which is fixed a jack gear which meshes with the common driving pinion on the main drive shaft.

In such former machines this earlier form of 30 driving system for the actuation of the feeding and drafting mechanisms has worked out satisfactorily only because the gear speeds were usually slow and the machines were operating less continuously than is required under modern operating conditions.

In the operation of present machines the spindle speed and also the speed of the front draft rolls have been increased greatly in the last decade over what had hitherto been the accepted 40 practice, and the continuous operation of such machines has been much more prevalent than in the past and brought about by the increased production demands under the modern practice. Under the conditions of increased speed and production the various gears employed to drive the front rolls wear out rather quickly and consequently require frequent replacement. The older type gear system also makes a great deal of noise when operating at the higher speeds required 45 under modern textile practice.

According to the present invention the change gears and the gear train driving mechanism therefor are arranged on and carried by a common mount which is so constructed and arranged 55 as to provide a compact unitary assembly of

gearing for mounting at one end of the machine. This unit mount comprises a bracket having two swing arms which carry the gearing for transmitting power from a common drive pinion to the two change gears. The swing arms are movable about a common pivot on the bracket and are arranged for independent movement into different adjusted positions thereon. One of the swing arms carries two carrier or idler gears and the other swing arm carries one carrier or idler gear, the said carrier or idler gears being driven by a positively-driven pinion on a drive shaft coaxial with the pivotal axis of said swing arms and power is transmitted to the change gears by the respective carrier gears that mesh therewith. The same twist is produced on both sides of the machine by employing change gears of the same number of teeth. If independent twist is desired on each side of the machine change gears having a different number of teeth will be used. Interchanging the positions of the two swing arms for effecting reversibility of twist provides that the front rolls will be driven in the proper direction when the tape drive drum is reversed in order to give the opposite hand of twist.

The lower front rolls arranged on both sides of the twisting machine, which is of the so-called double-sided type, are driven by chains and sprocket wheels. Also, the common drive pinion that drives the carrier gears of the gear trains is chain driven from a sprocket wheel which is mounted on the main drive shaft for the machine. The use of chains provides wide flexibility of drive of the various mechanisms and affords a wide range of location of the front rolls and the main driving shaft. The wide latitude in change gear sizes enables the advantage of wide range of possible twist.

Referring to the drawings in detail, and particularly to Fig. 1, there is shown elements of a twister frame comprising the head end frame member 10 having box sides, the stationary rails 11, 11' which support the spindles 12, 12', the vertically reciprocable ring rails 13, 13' which carry the rings and their travelers, and the bottom front drawing rolls 14, 14' which deliver the yarn to the spindles 12, 12' for the twisting and packaging operations, all of which parts may be of the usual construction or arrangement employed in such machines.

Upon the outer ends of the bottom front rolls 14, 14' disposed within the confines of the head end frame member 10, are fixed sprocket wheels 15, 15' which by sprocket chains 16, 16', of the silent type, are connected to and driven by sprocket wheels 17, 17' removably mounted on jack shafts 18, 18'. As illustrated in Fig. 8, the jack shafts 18, 18' are rotatably supported at their inner end portions in suitable ball bearings 19 housed within triangular-shaped brackets 20, 20', which are bolted to suitable lands formed at the upper corners of the mount or bracket 25 on which all the twist gearing mechanism is mounted for providing a unitary gearing assembly for mounting on the head end frame member of the machine.

Upon the jack shafts 18, 18' are removably mounted the change gears 21, 21' which are driven by the gearing mechanism that will be hereinafter described in detail. Shoes 22, 22' pivoted to the outer ends of the curved arms 23, 23' are pressed by suitable springs 24, 24' against the lower runs of the sprocket chains 16, 16' to maintain them properly tensioned.

The unit assembly of gearing for driving the

bottom front drawing rolls 14, 14' consists of the unit mount or bracket 25 which, as above mentioned, is attached to the head end frame member of the twisting machine. As shown in Figs. 2 and 3, this bracket comprises an upper plate section 26 and a lower raised, hollow, arcuate apron section 27 integral with the upper plate section. Concentric with the circularly curved perimeter of the arcuate section 27 and formed in the front face thereof is an arcuate T-slot 28 the opposite ends of which are open and terminate at the bottom edges of the depending legs 29, 29' which form the lower part of the arcuate apron section 27. The legs 29, 29' are symmetrically disposed on the apron section 27 and have flat opposed side faces which terminate at their inner ends in a semicircular opening concentric with the arcuate apron section and provide a relatively deep vertical slot extending upwardly from the bottom of the apron section when it is mounted in place on the machine.

Upon the sleeve-like hub 30 of a bearing member 31 concentric with the arcuate apron section 27 and affixed thereto by bolts 32 passing through a circular flange 33 are movably mounted two swing arms 34 and 35 which carry the intermediate or carrier gears 36, 37 and 38 that transmit the driving power from the drive pinion 40 to the two change gears 21 and 21'. As shown in Figs. 3 and 4, the pinion 40 is keyed to the outer end of a stud shaft 41 mounted in ball bearings 42 disposed within the cylindrical bore 43 of the bearing member 31. The stud shaft 41 extends through the bearing member 31 into the hollow rear portion of the arcuate section 27 and upon the inner end of the shaft 41 within the circularly curved cavity of the arcuate section 27 is fixed a sprocket wheel 45 which by a sprocket chain 46 of the silent type is connected to one of the sprockets of a double sprocket wheel 47 keyed to the outer end of the main drive shaft for the machine. Power is transmitted from the main shaft 48 and the double sprocket 47 by means of the chain 49 and the sprocket wheel 50 to the shaft 51 which shaft serves to drive the traverse operating mechanism of the machine. Traversing mechanisms of various kinds are in common use in spinning and twisting machines of this class, and as the traversing mechanism forms no part of my present invention I have not deemed it necessary to illustrate or describe the same in detail.

The chain 46 is engaged by an idler sprocket 52 which is loosely rotatable on a slide arm 53 adjustably secured to the end frame 10 by a bolt 54 passing through a slot 54' in the arm 53. The idler sprocket 52 engages the slack side of the chain 46, and said sprocket is adjusted to take up the slack therein by loosening the bolt 54 and then sliding the arm 53 relative to said bolt until the sprocket has pushed all slack out of the chain after which the slide arm and the sprocket are maintained in their adjusted positions by tightening the bolt 54 to rigidly secure the arm to the end frame member 10.

As shown more clearly in Figs. 2 and 3, the swing arm 34 carries the carrier gear 36 which meshes with the driving pinion 40 and the change gear 21, while the swing arm 35 carries the intermediate or carrier gears 37 and 38 which have meshing engagement with each other and form a gear train in which the inner gear 37 meshes with the drive pinion 40 and the outer gear 38 meshes with the change gear 21'.

The carrier gears 36, 37 and 38 are rotatably mounted by the sets of ball bearings 55, 56 and 57 respectively on the short shafts or studs 58, 59 and 60 which are suitably fixed at their inner ends in the swing arms 34 and 35.

The change gears 21 and 21', as above mentioned, are removably mounted on the outer end of the jack shafts 18 and 18', and one or both gears may be removed and replaced by a gear of larger or smaller size carrying the proper number of teeth to provide the desired twist per inch in the yarn. Also, the speed ratio between the lower front rolls 14, 14' and the jack shafts 18, 18' respectively may be changed by removing and replacing the sprockets 17 and 17' by either larger or smaller sprockets.

When it is desired to make a change in the hand of the twist, i. e. from right to left hand and vice versa, the positions of the swing arms 34 and 35 are exchanged which is accomplished by loosening clamping bolts 65 and 66 from the T-headed nuts 67 and 68 disposed within the arcuate slot 28, by which the swing arms 34 and 35 are securely clamped in position on the apron 27, and then swinging the free swing arms around the hub 30 to take positions on the other side of the hub 30 with the idler gears 36 and 38 in mesh with the change gears 21' and 21 respectively.

It will thus be seen that by the described mounting of all of the twist gearing in a compact unit assembly on the head end of the machine and the flexible connection of the sprocket wheels 15, 15' and 17, 17' by the sprocket chains 16, 16' respectively the advantage of flexibility of location of the front drawing rolls 14, 14' will be secured while maintaining an extremely wide range of possible twist per inch depending upon the size of the change gears 21, 21' employed.

In accordance with the present construction, advantage is gained in that the tooth speed of the gear system is always the same regardless of the size of the change gears that are used. The advantages of reversibility of twist and also independent twist are accomplished with fewer studs and gears as well as smaller gears than has to my knowledge been accomplished before. These advantages are important since ball bearings and their mountings are expensive. Other advantages are: low tooth speeds at all times regardless of the size of the change gears employed; quiet operation and longer life of gears because of the said low tooth speed; increased life of the unit as a whole because of the use of ball bearing mountings for all gears; the reduction of the number of studs and gears to a minimum; economy in manufacturing the unit because of said reduction in the number of studs and gears, and because of the reduced diameters of the gears; and also reduced manufacturing cost and other obvious advantages due to the fact that the assembly is constructed as a single self-contained unit.

I claim:

1. In a spinning or twisting frame, the combination with an end frame and front drawing rolls mounted on opposite sides thereof, of a driving system for the front rolls comprising a main driving pinion; means for actuating said driving pinion; two change gears to be driven; gearing actuated by said driving pinion and adapted to actuate said change gears; a flexible drive between each of said change gears and the front rolls to be driven, said flexible drives each comprising a driving wheel, a driven wheel and a flexible connection between said wheels, the said

driving wheel being connected to and driven by one of the change gears and the driven wheel being connected to the front roll to be driven; and a demountable support for said driven change gears and their driving gearing providing a unit assembly therefor attached to said end frame.

2. In a spinning or twisting machine, the combination with an end frame and front rolls mounted on opposite sides thereof, of a driving system for the front rolls comprising a main driving pinion, means for actuating said driving pinion, two change gears to be driven, gearing actuated by said driving pinion and adapted to actuate said change gears, a chain gear drive between each of said change gears and the front rolls to be driven, the said chain gear drives each comprising a chain and two sprockets one of which is adapted to be actuated by the change gear associated therewith and the other sprocket being connected to the front roll to be driven, and a demountable support for said driven change gears and their driving gearing providing a unit assembly therefor attached to said end frame.

3. In a spinning or twisting machine, the combination with an end frame and front rolls mounted on opposite sides thereof, of a driving system for the front rolls comprising a main driving pinion, means for actuating said driving pinion, two detachable change gears to be driven, two swing arms each adapted to be independently adjusted about a common axis, a carrier gear on one of said arms meshing with said main driving pinion and one of said change gears, a gear train on the other swing arm one of the terminal gears of said train meshing with said main driving pinion and the other terminal gear of said train meshing with the second change gear, a chain gear drive between each of said change gears and the front rolls to be driven, the said chain gear drives each comprising a chain and two sprockets one of which is adapted to be actuated by the change gear associated therewith and the other sprocket being connected to the front roll to be driven, and a demountable support for said swing arms, said driven change gears and their driving gearing providing a unit assembly therefor attached to said end frame.

4. In a spinning or twisting machine, the combination with an end frame and front rolls mounted on opposite sides thereof, of a driving system for the front rolls comprising a main driving pinion, a driven sprocket adapted to actuate said main driving pinion, means for actuating said driven sprocket, two driven shafts, a detachable change gear on each of said shafts for driving the same, two swing arms each adapted to be independently adjusted about a common axis, a carrier gear on one of said swing arms meshing with said main driving pinion and one of said change gears, a carrier gear train on the other swing arm one of the terminal gears of said train meshing with said main driving pinion and the other terminal gear of said train meshing with the change gear to be driven by said train, means for locking said swing arms in their respective adjusted positions to maintain the gearing thereon in operative relation with the change gears to be driven, a chain drive between each of said change gears and the front rolls to be driven, the said chain gear drives each comprising a chain and two sprockets one of which is adapted to be actuated by the change gear associated therewith and the other sprocket being connected to the front roll to be driven, and a mount supporting said swing arms, driven

shafts and the change gears providing a unit assembly attached to said end frame.

5. In a spinning or twisting machine, the combination with an end frame and front rolls mounted on opposite sides thereof, of a driving system for the front rolls comprising a main driving pinion, means for actuating said driving pinion, two driven shafts, a detachable change gear on each of said shafts for driving the same, two swing arms each adapted to be independently swung about the axis of said main driving pinion into adjusted positions, a carrier gear on one of said swing arms meshing with said main driving pinion and one of said change gears, a carrier gear train on the other swing arm one of the terminal gears of said train meshing with said main driving pinion and the other terminal gear of said train meshing with the second change gear, means for locking said swing arms in their respective adjusted positions to maintain the gearing thereon in operative relation with the change gears to be driven, a chain drive between each of said change gears and the front rolls to be driven, the said chain gear drives each comprising a chain and two sprockets one of which is adapted to be actuated by the change gear associated therewith and the other sprocket being connected to the front roll to be driven, and a mount supporting said swing arms, driven shafts and the change gears providing a unit assembly mounted on said end frame.

6. In a spinning or twisting machine, the combination with an end frame and front rolls mounted on opposite sides thereof, of a driving system for the front rolls comprising a main driving pinion, means for actuating said driving pinion, two driven shafts, a detachable change gear on each of said shafts for driving the same, two swing arms each adapted to be swung about the axis of said main driving pinion into adjusted positions, a carrier gear on one of said swing arms meshing with said main driving pinion and one of said change gears, a carrier gear train on the other swing arm one of the terminal gears of said train meshing with said main driving pinion and the other terminal gear of said train meshing with the second change gear, said swing arms being capable of movement from one side of the pivot to the other to connect the gearing carried by said arms with the change gears whereby the positions of said swing arms may be interchanged so as to permit the actuation of the change gears by the gearing on either swing arm, means for locking said swing arms in their respective positions to maintain the gearing thereon in operative relation with the change gears to be driven, a chain drive between each of said change gears and the front rolls to be driven, the said chain gear drives each comprising a chain and two sprockets one of which is adapted to be actuated by the change gear associated therewith and the other sprocket being connected to the front roll to be driven, and a mount supporting said swing arms, driven shafts and the change gears providing a unit assembly mounted on said end frame.

7. In a twisting machine, the combination of a stub shaft, means for driving said shaft, a pinion on said stub shaft and driven thereby, two driven shafts, chain drive wheels carried by said driven shafts and driven thereby, change gears removably mounted on said driven shafts, gearing intermediate each said change gear and said pinion for driving said change gears and the chain drive wheels, and mounting means for said inter-

mediate gearing comprising separate swing arms independently adjustable about the axis of said stub shaft, together with means for locking said swing arms in their respective adjusted positions.

- 5 8. In a twisting machine, the combination of a stub shaft, a sprocket wheel for driving said shaft carried at one end thereof, a pinion on the other end of said shaft and driven thereby, two driven shafts, sprocket wheels on and driven by said driven shafts, change gears removably mounted on said driven shafts, gearing intermediate each said change gear and said pinion for driving said change gears, driven shafts and sprocket wheels, and a mount for said driven shafts and gearing comprising separate swing arms independently rotatable about the axis of said stub shaft and means for locking each said swing arm in its adjusted position about said axis.
9. In an actuating mechanism for spinning and twisting machines, a main driving pinion, means for actuating said driving pinion, two driven shafts, a detachable change gear on each of said shafts for driving the same, two swing arms each adapted to be adjusted about a common axis, a carrier gear on one of said swing arms meshing with said main driving pinion and one of said change gears, a carrier gear train on the other swing arm one of the terminal gears of said train meshing with said main driving pinion and the other terminal gear of said train meshing with the change gear to be driven by said train, a mount supporting said main driving pinion, swing arms, driven shafts and the change gears providing a unit assembly for attaching to one end of the machine, and means for locking said swing arms in their respective adjusted positions on said mount with all of said gearing in operative relationship.
- 10 10. In an actuating mechanism for spinning and twisting machines, a main driving pinion, means for actuating said driving pinion, two driven shafts, a detachable change gear on each of said shafts for driving the same, two swing arms each adapted to be independently adjusted about a common axis, a carrier gear on one of said swing arms meshing with said main driving pinion and one of said change gears, two carrier gears on the other swing arm one of which carrier gears meshing with said main driving pinion and the second carrier gear meshing with the other change gear to be driven, a mount supporting said main driving pinion, swing arms, driven shafts and the change gears providing a unit assembly for attaching to one end of the machine, and means for locking said swing arms in their respective adjusted positions on said mount with all of said gearing in operative relationship.

11. In an actuating mechanism for spinning and twisting machines, a main driving pinion, means for actuating said driving pinion, two driven shafts, a detachable change gear on each of said shafts for driving the same, two swing arms each adapted to be swung about the axis of said main driving pinion into adjusted positions, a carrier gear on one of said swing arms meshing with said main driving pinion and one of said change gears, a carrier gear train on the other swing arm one of the terminal gears of said train meshing with said main driving pinion and the other terminal gear of said train meshing with the change gear to be driven by said train, a mount supporting said main driving pinion, swing arms, driven shafts and the change gears providing a unit assembly for at-

taching to one end of the machine, and means for locking said swing arms in their respective adjusted positions on said mount with all of said gearing in operative relationship.

12. In an actuating mechanism for spinning and twisting machines, a main driving pinion, means for actuating said driving pinion, two driven shafts, a detachable change gear on each of said shafts for driving the same, two swing arms each adapted to be independently adjusted about a common axis, a carrier gear on one of said swing arms meshing with said main driving pinion and one of said change gears, two carrier gears on the other swing arm one of which carrier gears meshing with said main driving pinion and the second carrier gear meshing with the other change gear to be driven, said swing arms being capable of movement from one side of the pivot to the other to connect the gearing carried by said arms with the change gears whereby the positions of said swing arms may be interchanged so as to permit the actuation of the change gears by the gearing on either swing arm, a mount supporting said main driving pinion, swing arms, driven shafts and the change gears providing a unit assembly for attaching to one end of the machine, and means for locking said swing arms in their respective adjusted positions on said mount with all of said gearing in operative relationship.

13. In an actuating mechanism for spinning and twisting machines, a support, two driven shafts, anti-friction bearings rotatably mounting said shafts on said support, a sleeve-like bearing housing affixed to said support, a drive shaft, anti-friction bearings rotatably mounting said drive shaft within said bearing housing, a driving pinion on the outer end of said drive shaft, two swing arms movably mounted upon the outer cylindrical portion of said bearing housing, each of said swing arms being capable of being swung about said bearing housing into adjusted positions on said support, a carrier gear on one of said swing arms meshing with said driving pinion and one of said change gears, two carrier gears on the other swing arm one of which carrier gears meshing with said driving pinion and the second carrier gear meshing with the other change gear to be driven, anti-friction bearings rotatably mounting said carrier gears on studs fixed to the respective swing arms, and means for locking said swing arms in their respective adjusted positions relative to said support with all of said gearing in operative relationship, said support providing a unit assembly of all of the above mechanism for attaching to one end of the machine.

14. An actuating mechanism for spinning and twisting machines comprising a support formed with an upper plate-like portion and a lower hollow raised arcuate portion, the front face of said arcuate portion being formed with an arcuate T-slot concentric with the circularly curved perimeter of said arcuate portion, a sleeve-like bearing member affixed to said lower arcuate

portion and co-axial therewith, a stub shaft journalled in said bearing member, a driving pinion on the outer end of said shaft, a gear on the inner end of said shaft within the hollow interior of said arcuate portion for actuating said stub shaft, two driven shafts rotatably mounted in said upper portion of said support, a detachable change gear on each of said shafts for driving the same, two swing arms movably mounted

10 upon the outer cylindrical portion of said bearing member, each of said swing arms being capable of being swung about said bearing member into adjusted positions on said support, a carrier gear on one of said swing arms meshing with said driving pinion and the second carrier gear meshing with the other change gear to be driven, and
15 means coacting with said T-slot for releasably securing said swing arms in their respective adjusted positions on said support with all of said gearing in operative relationship, said support providing a unit assembly of all of the above
20 mechanism for attaching to one end of the machine.

15. An actuating mechanism for spinning and twisting machines comprising a support formed with an upper plate-like portion and a lower hollow raised arcuate portion, the front face of said arcuate portion being formed with an arcuate T-slot concentric with the circularly curved perimeter of said arcuate portion, a sleeve-like bearing member affixed to said lower arcuate portion and co-axial therewith, a stub shaft, anti-friction bearings rotatably mounting said shaft in said bearing member, a driving pinion on the outer end of said shaft, a gear on the inner end of said shaft within the hollow interior of said arcuate portion for actuating said shaft, two driven shafts, anti-friction bearings rotatably mounting said driven shafts in said upper portion of said support, a detachable change gear on each of said driven shafts for driving the same, two swing arms movably mounted upon the outer cylindrical portion of said bearing member, each of said swing arms being capable of being swung about said bearing member into adjusted positions on said support, a carrier gear on one of said swing arms meshing with said main driving pinion and one of said change gears, two carrier gears on the other swing arm one of which carrier gears meshing with said driving pinion and the second carrier gear meshing with the other change gear to be driven, anti-friction bearings rotatably mounting said carrier gears on studs fixed to the respective swing arms, and means coacting with said T-slot for releasably securing said swing arms in their respective adjusted positions on said support with all of said gearing in operative relationship, said support providing a unit assembly of all of the above mechanism for attaching to one end of the machine.
